METHOD AND MEANS FOR THE TRANSMISSION OF PICTURES AND THE LIKE

Application filed April 19, 1928, Serial No. 271,296, and in Austria April 12, 1927.

This invention relates to improvements in and connected with methods of and means for the long distance transmission of pictures, diagrams and other impressions.

- 5 Various methods and apparatus for transmitting long distance light images and general television have already been devised, these being provided with a rotating drum and a writing contrivance shifting transversely of the drum. The various systems known consist of a rail, adjusted in parallel with and alongside of the drum axis, for carrying the traveling recording pin or feeling device which is connected compulsorily 10 with the driving shaft of the drum by means of a suitable traverse. With some systems a screwed spindle effecting the longitudinal movement either of the recording pin, or of the cylinder, is connected with an extension 15 of the cylinder, so as to simplify the construction and to increase the reliability of the apparatus. These systems need an arrangement for producing synchronism between the transmitter and the receiver. It is 20 further known that in various modes of long distance transmission, the half-tints or half tone photographs to be transmitted have, by means of a screen to be divided up in separate elements, and it is also known in connection 25 with these known methods to employ synchronizing arrangements including a relay at the receiving end which is put in action by the transmitter at the conclusion of a picture line.
- 30 Important features of this invention are among others, improvements of the recording and manipulating contrivances of long distance transmitting apparatus, and a combination of these modified mechanisms with a system of synchronization using a relay connected with the telephotography or picture circuit.

- 35 Another feature of this invention is an improvement of the arrangement for moving the stylus or other such device in relation to the drum in the direction of its axis. Usually the cylinder and the spindle have a common axis, and the stylus is carried on a carriage supported on rollers, this carriage 40 also carrying a wheel with a knife edge to en-

gage the screw-threaded spindle. Should the spindle continue rotating, while the apparatus is in operation, after the stylus has reached the proper end of its travel, the mechanism may be damaged. To prevent 55 this, this invention provides that the part of the mechanism interacting with the screw-threaded spindle, rides near the end of its travel, on to a body conveniently shaped, rotating with the spindle. This body has a 60 groove cut in its surface for retaining the knife-edged wheel, so that the carriage is lifted and retained in the lifted position, even if the spindle should continue rotating. In consequence of this automatic lifting-off of 65 the recording and manipulating parts to a raised position, any damage of the films and of the recording surface is prevented.

A further improvement in this invention is the use of a relay in the telephotography- 70 circuit in connection with the modified apparatus particularly in case of transmitting half tone photographs. For purposes of an electrochemical writing process it is of special advantage to divide up the pictures, diagrams and other impressions to be transmitted by means of linear screen, in which case the scanning is effected in a normal ratio to the lines of the screen. By this method alone, which avoids the disadvantages of a 75 modulation of intensity, it is possible to produce half-tints equal in quality to those obtained by optical means. These half-tints, when used as clichés, look equally nice in print. The combined use of such images that 80 have been divided up in lines, in connection with a synchronization method with a relay and the measure to specially regulate the current between transmitter and receiver, for the purpose of improving the quality of the 85 pictures transmitted, are further points of interest of this invention. It is of vital practical importance that the same apparatus should be used for transmitting and receiving, which has until now not been done with 90 the system working with a relay.

As above explained, in practice a line screen is used which, in the case of the usual spiral scanning of the transmitter foil or film, suitably prepared and stretched on a 95 100

drum, is passed under the stylus effecting the scanning, at right angles to the screen lines. When the stylus slides transversely over the screen lines, it will first touch the bare conducting surface of the picture support, and then again the insulating line; according to the different width of the screen lines, that is to say according to the degree of light of the corresponding picture portions, the successive current impulses will be therefore longer or shorter, and will act accordingly at the receiving end. The number of the picture elements to be transmitted, that is to say the fineness of the screen used, is dependent on the advance or feed of the stylus, that is to say on the pitch of the screw-threaded spindle used for the purpose. If the number of threads per unit of length is increased, all other conditions remaining equal, there will take place a considerable lengthening of the time of transmission, so that for that reason, in order to enable optimum time of transmission to be maintained for the same size of picture, the wealth of detail of the pictures to be transmitted cannot be raised beyond a certain measure.

To sum up, the advantage is ensured that in the case of half tone pictures and drawings, more detail can be obtained without increasing the time of transmission, as well as the possibility of transmitting thinner lines parallel to the direction of scanning. It must be further mentioned that the use and application of this stylus to other apparatus, also comes within the range of the present invention.

The synchronizing arrangement employed in the above described modified apparatus for long distance transmission is now to be described.

In the method with which this invention is concerned, the transmitting apparatus is operated continuously, while the recording appliances to be synchronized at the receiving end, is operated more rapidly, but is stopped after every rotation, only to be released by the incoming signal from the transmitter, thereupon starting another revolution synchronously with the transmitting station. Usually, very strong motors are used for the receiving apparatus, the coupling being so arranged, that the recording contrivance alone is stopped, the motor meanwhile remaining in action. With this arrangement it is unavoidable that, by the changes of strain resulting from the arresting of the receiving apparatus, some disparity should occur especially if inexpensive and not very powerful driving motors are employed.

To achieve good results even when using light motors, it will be sufficient to stop the scanner device of the transmitter in the same way as in the receiver, the relay releasing the stopping or locking device at the receiver end, and thus insuring equable characteris-

tic of movement (synchronization) during the time of one period of utilization, if the apparatus at the transmitter and at the receiver are simultaneously started and are driven by motors of equal power. The couplings used between the motor and the feeler or scanning device should also run equally. By this method synchronization is greatly perfected, and a far more uniform movement in the intervals between the phases of rest is attained. The advantage of this system also is, that by the uncoupling of the relay of the stopping or locking device at the receiving end, no timing of any pendulum or any contrivance replacing a pendulum is necessary, nor any separate adjustment of phase, the apparatus being automatically started and just so stopped at the completion of every picture transmission.

A further modification will now be described.

It is known that the mechanical couplings for connecting the motor to the drum are mostly made in the form of slipping friction couplings which have the drawback that the driving motors are braked when the drum is stopped and therefore, in order to avoid acceleration when the drum is released, the motor has to be made as powerful as possible. If on the other hand in order to avoid excessive braking the coupling is adjusted so that its action is not powerful enough, the driving of the rotating drum does not take place at once, and the whole working for the purpose of synchronization is jeopardized. Moreover, it is difficult to construct such couplings mechanically in such a manner that their action always remains the same and that they do not require any adjustment or attention for a long time.

For avoiding this last fault, it is further known to use electromagnetic couplings which can be used exactly like friction couplings, but owing to the elimination of the parts subject to wear and to the possibility of varying the electric current energizing them, their action can be easily modified and maintained constant.

The drawback of these arrangements is that they consume too much energy for their operation, as in the absence of parts rubbing against each other the torque has to be transmitted through an air gap, and further that, as already stated, there takes place a braking of the driving motor when the drum is stopped, that is to say, in the operation of the coupling.

The invention solves the problem of improvement of such couplings used in the picture transmission apparatus, in such manner that, all the above mentioned drawbacks are eliminated, that is to say the driving motor is no longer braked, and on the other hand, whilst avoiding as far as possible expensive constructional elements, great constancy with

ease of attendance is ensured. A particular advantage is that owing to the exceedingly small load fluctuations and absolute load, even very weak and therefore cheap driving motors, for instance spring mechanisms, can be used, provided only that they possess a sufficient degree of uniformity.

Another advantage over any friction couplings is that there cannot be possibly any dependence on the material of any friction covering, that consequently complete uniformity of action at any point of the circumference is guaranteed, that no wear can take place and therefore, even after a long period of working, no adjustment or generally any setting becomes necessary.

According to the invention a magnetic coupling is utilized in such manner that it acts as a rigid coupling only when the transmission of a torque is desired; in the other case however, that is to say during the time of locking of the writing device, the coupling is completely disconnected so that the driving gear does not have to perform any frictional work. At the moment when the locking device is released, the coupling is also automatically operated again, namely, in such a manner that the parts to be driven, are at once put in motion, without risk of any slipping.

The necessary instantaneous forces of acceleration are also supplied by a weak driving motor, provided that the constructional elements to be driven are correctly proportioned.

It is known to employ in apparatus for distance transmission of pictures, methods of synchronization in which at given time intervals, for instance after each revolution of the cylinder carrying the transmitter film or foil, a current impulse or, in the case of wireless transmission, a train of waves is sent from the transmitter, which is used for the synchronization in the receiver, in such a manner that by means of a relay a stopping or locking device is released, so that both transmitting and receiving apparatus begin a new revolution synchronously. It is also known to use for this purpose slip rings rotating with the transmitter cylinder and provided with the suitable contact segments, or polished strips of suitable width transversely over the whole suitably prepared metal transmitter film or foil.

According to the invention, an improvement in such a process of synchronization is obtained by transferring the metal contact extending throughout the whole width of the transmitter cylinder, so that it constitutes the device which is used for mechanically securing or fixing the transmitter foil to the cylinder. This ensures that the space otherwise used for the securing or fixing device, will not be lost for the picture surface, and on the other hand that the transmitter foil will not have to be provided in any extra way with a synchronizing strip, and that the bright

contact strip could be made very accurately and of sufficient mechanical strength. A suitable construction is for instance to make the fixing clip with a cross section in the form of a segment of a circle, fitting the correspondingly recessed drum of the transmitter. Another possible construction is to use for the sending of the synchronization current impulse at each revolution a group of springs controlled by a suitable cam or the like, which controls all the switching processes, that is to say sends the synchronization impulse and moreover produces the necessary time interval before and after the latter.

As already stated, on the receiver there is used a relay which is operated by the incoming current impulse and thereby produces synchronization in any desired manner by making a suitable contact, for instance, for the release of a locking device for writing drum of the receiver.

It is known that for that purpose polarized relays are used which are arranged in the picture circuit of the receiver and so connected by means of a suitable slip ring provided with segments, that the direction of the synchronization impulse is such that the armature or keeper of the relay is turned over and effects the desired contact.

According to the invention, an improvement is effected in such an arrangement by making the connection, when using relays, in such a manner that the relay is normally short circuited, and is switched into the picture circuit only immediately before the incoming current impulse. This ensures that the resistance and the inductivity of the sensitive, and therefore mostly high ohmic relay will not become perceptible in the picture current, which is of special importance in the case of wireless receiver, further, as the relay can attract only just before the arrival of the synchronization impulse, the advantage is obtained that the possibility of a faulty synchronization on account of atmospheric disturbances in the case of wireless transmission is greatly reduced, and moreover in the event of any getting out of step during a period of synchronization, phase coincidence will be obtained again in a reliable manner at the next period.

It is preferable to combine all the spring contacts in a single group, namely all those which are used for the sending of the synchronization impulse, for the short circuiting of the relay and further also all the switches used say in magnetic couplings. With a proper construction, practically all of them can be controlled by means of one projection or cam, and therefore, in addition to a greater simplicity, a substantially greater reliability of working will be ensured.

In order to enable the invention to be readily understood, reference is made to the accompanying drawings, which illustrate

diagrammatically and by way of example, suitable arrangements for the carrying out of these improvements, in which drawings:

Fig. 1 is a plan view somewhat diagrammatic of one form of scanning and recording device;

Fig. 2 is a diagram illustrating the electrical connections of the recording device shown in Fig. 1;

Fig. 3 is a diagram illustrating the electrical connections for the magnetic clutch, and mechanism actuated by the synchronizing signal;

Fig. 4 is a side view of the stop mechanism;

Fig. 5 is a plan view of the stop mechanism.

Figure 1 shows one mode of construction of the scanning and of the recording appliances. S' is a spindle mounted in the bearings L_1 and L_2 , the drum Z bearing the recording surface, being coaxial and joined therewith. The spindle and drum are restrained from endwise movement. The stylus P is mounted on a carriage W to be movable parallel with the drum Z . The carriage carries wheel R' , which engages in the threads or grooves of the spindle. If the whole arrangement W moves from the right to the left, the wheel R' moves into a continuation of the thread formed in the cone K' , and thus rises and lifts the stylus P off the cylinder Z . In the place of its greatest dimension the cone K' has a rut, in which the wheel R' is retained, even if the spindle S' continues rotating.

A constructional example of the synchronizing arrangement as employed with the improved apparatus is schematically shown in Figure 2. The picture current, strengthened for example by means of the three element vacuum tube V , passes through the relay R and the recording surface Z , here formed as a drum with the recording or feeler pin S . The relay R works a contact K which closes a local battery circuit for removing a stop H and thus releasing the drum. The relay R is mechanically so inert, or electrically so retarded, that, even while transmitting half-tints which ought to be divided up into their separate elements by means of a suitable screen, it permanently remains attracted and consequently only releases the receiving drum with the assistance of contact K if, at the same moment, the scanning device at the transmitting end, starts a new picture line.

Figure 3 schematically shows one mode of construction of electromagnetic coupling for obtaining better synchronization.

On the spindle A is mounted the magnet M with its armature A_n . In practice the magnet M is made preferably in the form of a flat pot magnet, and the armature A_n in the form of a disc arranged opposite it and prevented from rotating on the spindle by a tappet N . One end of the winding of the magnet M is

connected to the body, the second end carried to a ring S_1 ; there is further provided a second ring S_2 which also carries the stop H for the locking drum spindle A . When the magnet M is supplied with current, for instance through a contact of a relay R , it will attract its armature B ; at the same moment the stop H will be released, and the contact K closed at the same time. This contact closes the circuit leading from the battery C through a group of spring-contacts, controlled by suitable cams or the like, and through the ring S_1 and the winding of the magnet M , so that the magnet M will attract and hold fast the armature A_n . The magnet M and the ring S_1 are mounted on one and the same sleeve which is loosely rotatable on the spindle A which at the same time also carries the gear wheel D effecting the driving, so that at the moment when the magnet M is energized by current, the armature A_n and owing to the tappet or driver N , also the spindle A and all the parts secured to it, will begin to rotate. The ring S_2 which is constantly connected with the body, is provided at a single point with an insulating part I which, in the position of rest, that is to say when the stop H engages with the armature B , is situated under the brush E . During the remainder of the revolution, the contact K is short circuited through the brush E and the ring S_2 , so that the coupling always remains operative, even when the relay R and therefore, through the magnet M_1 the armature B , and the contact K are not operated.

The operation is as follows:

In the position of rest when the coupling is disconnected, the driving motor which engages with the gear wheel D , will have to overcome only the very slight friction caused on the spindle A_1 by the magnet M , ring S_1 and gear wheel D , as the armature A_n rests on the magnet M without the slightest pressure. If the relay R is switched in for a short time, the magnet M will be energized in the manner already described through the magnet M_1 , armature B and contact K , and in that way nearly a rigid connection will be made between the magnet M and the armature A_n . The forces produced in the magnetic coupling are so great, provided that the dimensioning is correct, that even a short sliding of the armature A_n on the magnet M is made impossible. All the parts will now participate in the rotation until the current is cut off from the magnet M , which takes place at the moment when the brush E or alternative spring-contacts reach the insulating part I . This takes place immediately before the completion of a full revolution and just before the stop H touches again the armature B . If the magnet M and the armature A_n are made of a suitable material, the forces between the two parts will cease to act at the moment when

the current is cut off. The same thing will then take place again as described.

It cannot therefore happen in such an arrangement according to the invention that the two coupling halves will slip on each other, that is to say the driving motor will always have to work under a practically constant load; whether the parts connected to the spindle A be driven or not. Moreover 10 the great forces produced, ensure that no material slipping of the coupling will take place, so that the greatest part of the faults otherwise occurring in such apparatus used for picture transmission, are avoided, and the 15 quality of synchronization is improved accordingly.

A further improvement in this apparatus relates to the locking device.

Since at the moment of locking of the 20 relating parts they are no longer acted upon by any torque, that is to say the electro-magnetic coupling was disconnected a short time before, and the last short fraction of the revolution is completed freely under the action 25 of momentum, it will happen as a rule that on contact with the stop, the rotatable parts will be thrown back, and therefore the stopped rotating parts do not always begin their new revolution from the exactly defined 30 position of the projection or the like utilized for the stopping. It is therefore necessary to provide for the construction of coupling according to the invention, also a new locking device, namely so that at the moment of 35 stopping, all the rotating parts should be coincidently and completely locked, so that the new revolution shall always start from the exact defined position.

A construction of the apparatus according 40 to this part of the invention is diagrammatically illustrated by way of example in Figures 4 and 5, in elevation and in side-view respectively.

To the rotatable parts of the apparatus is 45 connected the disc S which is provided at one point with a recess P into which fits the correspondingly shaped projection N₁. This projection is secured to the armature B₁ which is mounted for instance on a spring F; 50 in front of the armature is arranged the magnet M₂ which effects the release in accordance with the preceding description of the coupling. Owing to the projection N₁ springing into the recess P and being lifted 55 out only at a suitable moment by the magnet M₂, a complete locking of the rotating parts is ensured, independently of any inertia and elastic rebound forces that may occur.

The hereinbefore described modification 60 and apparatus represent in their combination a considerable advance in the long distance transmission of light images and general television. Measures to combine some, several or all of these innovations with all 65 ready existing apparatus, might prove most

advantageous and such combinations certainly are within the scope of this invention.

What I claim and desire to secure by Letters Patent of the United States is:—

1. A device for the electrical reception of 70 pictures, comprising means for receiving both picture signals and synchronizing signal, a rotating receiving drum, and driving means therefor, an electromagnetic clutch which is electrically energized to couple the 75 receiving drum to the driving means, means for stopping the receiving drum at the completion of each revolution, means operated by the synchronizing signal for releasing the receiving drum at the commencement of each 80 revolution and for energizing the said clutch, other means for maintaining the clutch electrically energized throughout substantially the remainder of the revolution while the picture signals are being received and means 85 operated by the picture signals for receiving a picture.

2. A device for the electrical reception of 90 pictures, comprising means for receiving both the picture signals and the synchronizing signal, a rotating receiving drum and driving means therefor, an electric magnetic clutch for coupling the receiving drum to the driving means, an electric magnetic device comprising a movable armature constituting 95 a stop for the receiving drum at the completion of each revolution, means for energizing said electromagnetic device to withdraw the stop and release the receiving drum at the commencement of each revolution, electric 100 contacts operated by the movement of the armature in releasing the drum to close the energizing circuit of the electromagnetic clutch, other means for maintaining said circuit closed during substantially the remainder of the revolution of the drum, and means operated by the picture signals for 105 reproducing a picture.

3. Apparatus according to claim 1 wherein 110 in the electromagnetic clutch is maintained energized after the synchronizing signal has ceased by means of a circuit in parallel with the aforesaid electric contacts and including an automatically operated switch for opening this circuit immediately before the drum 115 completes a full revolution.

4. Receiving apparatus for transmitted 120 pictures comprising a rotatable drum, means cooperating with the drum to reproduce the transmitted picture, driving means for the drum, an electromagnetic clutch interposed between the drum and the driving means, a stop for the drum operative at the completion of each revolution, an electromagnetic device for releasing the drum operated on receipt of a synchronizing signal, a switch also operated by the said electromagnetic device for closing an energizing circuit of the clutch, and switch contact means operated by the 125 rotation of the drum for maintaining the 130

clutch energized during substantially the remainder of a revolution after the synchronizing signal has ceased.

5. A device for the electrical reception of pictures, comprising a drum for holding a sensitized body, a stylus coacting with the sensitized body, a continuously rotated element, an electrical clutch between the continuously rotated element and the drum included in an electrical circuit, means for stopping the drum at the conclusion of each revolution, electrically actuated means for removing the stop, means for momentarily closing the circuit through the clutch when the stop is removed, other means for closing said circuit through the clutch responsive to the setting of the drum in motion, and means for opening said last mentioned circuit-closing means, responsive to the completion of the 20 revolution of the drum.

6. A device for the electrical reception of pictures, comprising a drum for holding a sensitized body, a stylus coacting with the sensitized body, a continuously rotated element, an electrical clutch between the continuously rotated element and the drum included in an electrical circuit, means for stopping the drum at the conclusion of each revolution, electrically actuated means for removing the stop, a switch in said circuit, means for closing the switch when the stop is removed, a second switch in said circuit in multiple with the first switch, means for closing the second switch, responsive to the setting of the drum in motion, and means for opening the second switch, responsive to the completion of the revolution of the drum.

In testimony whereof I have signed my name to this specification.
